(57) **CLAIM**

I claim the ornamental design for a bottle-shaped ukulele, as shown and described.

DESCRIPTION

FIG. 1 is a front view of a bottle-shaped ukulele of the claimed design;

FIG. 2 is a right side view of the bottle-shaped ukulele of FIG. 1; the undisclosed left side view being a mirror image thereof; FIG. 3 is a back side view of the bottle-shaped ukulele of FIG. 1;

FIG. 4 is a bottom side view of the bottle-shaped ukulele of FIG. 1; and,

FIG. 5 is a top side view of the bottle-shaped ukulele of FIG. 1.

The broken lines in FIG. 1, showing a sound hole, represent the portions of the ukulele which form no part of the claim.
